UNITED STATES PATENT OFFICE.

ANTHIME BOISVERT, OF VICTORIAVILLE, QUEBEC, CANADA.

SLICING MACHINE.

Application filed February 4, 1926. Serial No. 86,043.

The present invention pertains to a novel slicing machine designed particularly for cutting bread and also suitable for cutting similar substances.

5 The principal object of the invention is the provision of a device of this character which cuts the entire loaf or body of material in one operation, as distinguished from machines of the present type in which a complete operation is required for each slice that is cut from the loaf or body.

In the accomplishment of this object, the apparatus is constructed in the nature of a frame on which is mounted a series of spaced 15 and parallel guide fingers. The cutting frame carrying a series of cutting blades is mounted for sliding movement with respect to the supporting frame in such a manner that the blades enter the spaces between the guide fingers in the cutting operation. The material to be sliced is placed on the fingers, and the cutting frame is depressed to pass through the material whereby the entire 20 body is sliced in one operation.

25 The invention further includes a construction whereby the sliced material is raised with the cutting frame and delivered into a receiving trough. Plates are provided at the fingers and on the cutting frame in such 30 a manner as to prevent expansion of the body after it has been penetrated by the cutting blades. On the return or upward stroke of the cutting frame, there is no restriction to upward movement of the sliced 35 body, and the blades being thus incapable of passing through the unexpanded body, merely raise it from the fingers. The cutting frame maintains an inclined position and thus sheds the sliced material into a 40 trough mounted in a suitable position.

The cutting frame is actuated by means of links attached to an operating shaft which carries an operating handle extending to the forward part of the supporting frame. 45 The shaft is surrounded by a spring having its ends connected to the supporting frame and the handle, so that upon release of the latter, it and the cutting frame are automatically returned to their normal position. 50 A pedal suitably connected to the operating shaft is also provided for operating the machine at the rear side of the supporting frame.

The invention is fully disclosed in the 55 following description and in the accompanying drawings in which:

Figure 1 is a perspective view of the device;

Figure 2 is a rear elevation thereof;

Figure 3 is a section on the line 3—3 of Figure 2;

Figure 4 is a detail section showing the manner of supporting the cutting frame;

Figure 5 is a longitudinal section of the cutting frame on the line 5—5 of Figure 1; and

Figure 6 is a detail perspective view showing the return mechanism.

Reference to these views will now be made by use of like characters which are 70 employed to designate corresponding parts throughout.

The device embodies a supporting frame consisting primarily of forward legs 1 and higher rear legs 2, both sets of legs being 75 joined by front rails 3, side rails 4 and rear rails 5 and 6. The upper ends of the front legs 1 are joined to the rear legs by means of additional horizontal side rails 7 equipped at both ends with handles 8 whereby the 80 entire structure may be readily lifted by two persons and carried from place to place. The inner sides of the rear legs 2 are provided with fixed track members 9 at the upper ends of which is placed a suitable spacing member 10. A transverse bar 11 is adapted to slide within the tracks, for the purpose of guiding the cutting frame presently to be described.

85 The cutting frame is a substantially rectangular member 12 having a plurality of cutting blades 13 mounted longitudinally therein. A pair of lugs 14 project backwardly from the sides of the frame near the upper end thereof and receive a rod 15 which is also passed through projecting portions of the bar 11. The ends of the rod are provided with cotter pins to prevent slipping.

90 Across the upper side rails 7 is laid a transverse bar 17 which lies adjacent the rear legs 2 as illustrated in Figure 3. This member serves as the supporting means of a plurality of curved fingers 18 which are parallel and spaced from one another. The 100 fingers may be constructed as separate members or as part of a longitudinal member which would be secured to the bar 17. At 105 one end of the series of fingers is mounted a vertical plate 19 as shown in Figure 1.

110 Near the base of the supporting frame, a pair of bearings 20 are secured to the back

of the rear legs 2. These bearings serve to support a shaft 21 to which are fixed a pair of parallel arms 22 and another pair of arms 23 which are parallel to one another but disposed at an angle to the arms 22. Links 24 are pivotally joined to the free ends of the arms 22, the remaining ends of these links being bifurcated as at 25 and pivotally connected to a rod 26 carried by the forward end of the cutting frame 5. Similar links 27 are pivotally connected to the free ends of the arms 23 and have their remaining ends also bifurcated as at 28 and loosely attached to the rod 15 as shown in greater detail in Figure 4. One side of the frame 5 carries a plate 29 which is opposed to the plate 19 for the purpose pointed out below.

One end of the shaft 21 carries a block 30 from which a handle 31 extends to the forward part of the supporting frame. Between the block and the adjacent bearing 20, a spring 32 is coiled around the shaft. One end of the spring is secured to the adjacent leg 2 and the other end to the block 30 as shown in Figure 6.

Between the forward legs 1 is mounted a trough consisting of a base 33 and sides 34. The trough is supported by a pin 35 passed through the base and having one end loosely mounted in one of the front legs while the other end passes through the other front leg. This projecting end is provided with a wing nut 36 whereby the inclination of the trough may be adjusted as illustrated in Figure 3. Also, a brace 37 is pivotally attached to one of the front legs 1 and adapted for engagement with the base of the trough in order to aid in supporting the latter. The free end of the brace passes through a strap 38 carried by the base, and the brace is further formed with a series of notches selectively to receive a tooth or similar device mounted within the strap (not illustrated).

In the operation of the device, the loaf of bread or other material to be sliced is placed within the curved fingers 18. One end of the loaf is placed against the plate 19, and the loaf is further supported by members 40 secured to fingers 18 and tending to hold the loaf against the vertical part of the fingers.

The handle 31 is now lifted, and the rearward movement of the arms 22 and 23 draw the cutting frame downwardly so that the blades 13 penetrate the material and pass through the spaces between the fingers 18. At this stage the material is held at its ends between the plates 19 and 29 whereby expansion is prevented. In other words, no separation of the slices formed by the cutters is permitted.

The handle 31 is now released and the spring 32 returns it to its normal position, whereby the cutting frame begins to rise. In engaging the sliced material from the bottom, the cutters do not pass through the ma-

terial owing to the fact that no spaces are formed between the slices. In the absence of resistance to upward movement of the material the latter is raised by the cutters of the frame during the return of upward stroke of the latter. The frame maintains an inclined position, as illustrated in Figure 3, whereby the sliced substance falls into the trough as soon as one end of the body is released from the plate 19.

The trough may be inclined if desired, and a receptacle placed beneath it to receive the contents discharged therefrom.

The machine may be operated from the rear of the supporting frame by means of a pedal 50 projecting from the block 30 as shown in Figures 2 and 6.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:

1. A device of the character described comprising a supporting frame, a plurality of guide fingers mounted on the frame, a cutting frame adapted for reciprocating movement with relation to the guide fingers, blades carried by the cutting frame adapted to pass between the fingers and remove the sliced material from the fingers in return movement, and a trough arranged to receive the sliced material from the cutting frame.

2. A device of the character described comprising a support frame, a plurality of spaced fingers adapted to support a loaf of material, a cutting frame adapted to be slidably reciprocated with relation to the fingers, cutting blades carried by the cutting frame adapted to pass between the fingers so as to initially cut the loaf and in return movement remove the sliced material from the fingers, and a trough supported on the support frame so as to receive the sliced material from the cutting frame.

3. A slicing device comprising a support frame, a plurality of separated guide fingers mounted on the frame, a cutting frame mounted for reciprocating movement on the support frame, a plurality of cutting blades carried by said cutting frame adapted to intermittently pass between the guide fingers to cut the material disposed thereon in its initial movement and remove the material from the fingers in its return movement, and a tiltable trough secured to the support frame adapted to receive the material as it is dropped from the cutting frame and convey the same to a suitable container.

4. A slicing device comprising a support frame, a series of separated fingers mounted

- on the support frame adapted to support a loaf of material in horizontal position, a cutting frame mounted for vertical reciprocating movement on the support frame, a plurality of blades secured to the cutting frame adapted to pass between the fingers during the operative movement of the frame, means for actuating the said cutting frame and blades including a shaft journaled transversely on the support frame, a bar mounted for vertical sliding movement in the frame adapted to support the upper end of the cutting frame, a plurality of arms fixed to the shaft, a plurality of links pivotally connected with the arms and with the cutting frame, and means for oscillating the said shaft.
- 5 In witness whereof I have hereunto set my hand.
- 10 ANTHIME BOISVERT.
